UNITED STATES PATENT OFFICE.

ELI MAYNARD LONG, OF GENEVA, NEW YORK, ASSIGNOR TO THE STANDARD OPTICAL COMPANY, OF GENEVA, NEW YORK, A CORPORATION OF NEW YORK.

EDGE-GRINDING MACHINE FOR LENSES.

1,272,474.

Specification of Letters Patent. Patented July 16, 1918.

Application filed June 2, 1916. Serial No. 101,282.

To all whom it may concern:

Be it known that I, ELI M. LONG, a citizen of the United States of America, and resident of Geneva, in the county of Ontario, in 5 the State of New York, have invented new and useful Improvements in Edge-Grinding Machines for Lenses, of which the following, taken in connection with the accompanying drawings, is a full, clear, and exact 10 description.

This invention relates to certain improvements in edge grinding machines for lenses, in which the rotary lens-holder is reciprocated axially across the face of a rotary 15 grindstone for reducing the lens to the desired form according to a predetermined pattern.

The main object is to increase the general 20 working efficiency of machines of this character,—

First, by reciprocating the lens-holder across the face of the grinder through the medium of an oil pump and adjustable means for reversing the direction of flow of 25 the oil from the pump and varying the distance of travel of the carriage at will.

Second, by rotating the lens (elliptical) at such differential speeds that all portions in 30 the perimeter thereof will be finished at approximately the same time, as distinguished from the usual method whereby the lens revolves at a uniform rate of speed which grinds the ends faster than the sides.

Third, by locating the axis of movement 35 of the rocking frame for the lens-holder in approximate alignment with the meeting points of the pitch circles of the driving gears to maintain a more uniform grinding action as the rocking support for the lens-holder oscillates.

Fourth, by providing for a quick opening and closing movement of one of the lens-clamping sections through the medium of a self-locking cam action capable of holding 45 said section in any position of adjustment.

Fifth, by bringing all of the adjustable parts to the front of the machine within easy reaching distance of the operator in one position.

50 Other objects and uses relating to specific

parts of the machine will be brought out in the following description.

In the drawings—

Figures 1 and 2 are, respectively, a top plan and a side elevation of an edge grinding machine embodying the various features of my invention.

Figs. 3 and 4 are enlarged vertical sectional views taken, respectively, on lines 3—3, and 4—4, Fig. 1.

Fig. 5 is an enlarged detail horizontal sectional view taken on line 5—5, Fig. 4.

Fig. 6 is an enlarged vertical sectional view taken on line 6—6, Fig. 2, showing particularly the lens-holder and the driving 65 means therefor, together with the cam mechanism for opening and closing the lens-clamping sections and the supporting frame for the various moving parts.

Figs. 7 and 8 are enlarged transverse vertical sectional views taken in the planes of lines 7—7 and 8—8, Fig. 6.

Fig. 9 is an enlarged vertical sectional view through the front portion of the machine taken on line 9—9, Fig. 1.

Figs. 10 and 11 are further enlarged horizontal sectional views taken in the planes of lines 10—10 and 11—11, Fig. 9.

Fig. 12 is an enlarged detail sectional view taken on line 12—12, Fig. 2.

Figs. 13, 14, 15, 16, 17, 18, 19 and 20 are diagrammatic views of the coöperative disks for driving the lens-holder at different speeds showing the different relative positions which the disks assume at starting and 85 at the end of each successive eighth turn during one complete revolution.

Fig. 21 is a face view of an elliptical lens, the radial lines showing the angles of movement corresponding to the successive positions of the disks.

Main supporting frame.

As illustrated, the main supporting frame consists of a substantially semi-circular 95 trough-like shell or casing —1— adapted to be secured in a horizontal position to any available support for receiving and inclosing the lower half of a rotary grindstone, presently described, and confining the waste 100

resulting from the grinding operation, together with the drip of water used in moistening the periphery of the grindstone, the lower front side of the trough being provided with a cleanout opening —2— and a closure —3— therefor, as shown more clearly in Fig. 3.

A shield —4— is secured to the upper rear edge of the main frame —1— and constitutes a part thereof and incloses the upper rear portion of the grindstone for confining the waste within the environs of the underlying trough.

A water-containing reservoir —5— is mounted upon the upper front end of the shield —4— directly over the grindstone and is provided with a suitable faucet —6— for supplying moisture to the periphery of the stone.

The front portion of the frame —1— is provided with an upwardly and forwardly inclined guideway —7— along and upon which is adjustable a movable section —8— for receiving and supporting a sliding carriage for the lens-holding frame and truing device, hereinafter described, the movable section —8— being held in its adjusted position by one or more clamping bolts —9—, Fig. 2.

30   *Grinding device.*

As illustrated, the grinding device consists of a rotary circular grindstone —10— adapted to revolve in the frame —1— and shield —4—, and for this purpose is mounted upon a rotary shaft —11— which is journaled in suitable bearings —12— on the upper edges of opposite sides of the frame —1— and is provided at one end with a pulley —13— adapted to be connected by a belt —14— to any available source of power, not shown, the grindstone being held against axial movement by suitable collars on the shaft at opposite sides of the grindstone.

45   *Sliding carriage and operating means therefor.*

The top of the adjusting section —8— of the main supporting frame —1— is disposed in a substantially horizontal plane and is preferably recessed to form a lengthwise guideway —15— running parallel with the axis of the grindstone shaft —11— in proximity to the front edge of the grindstone —10— for receiving and guiding a sliding carriage —16— which is held against upward displacement by dove-tail connections, shown more clearly in Fig. 3.

The adjacent sides of the section —8— and carriage —16— are chambered longitudinally at —17— and —18—, respectively, for receiving a hollow cylinder —19— which is rigidly secured to the bottom of the section —8— parallel with the guideway —15—

for receiving a reciprocating piston —20—, 65 Fig. 9, having oppositely projecting piston rods —21— extending through suitable glands in corresponding end heads —22— of the cylinder, said piston —22— and its rod —21— constituting a plunger which is 70 adapted to be operated in reverse directions by a fluid under pressure, as oil, through the medium of a power-driven pumping device, hereinafter described, and also serving to transmit similar motion to the carriage —16—.

For this latter purpose, the carriage is provided with pendent abutments —23— and —24— engaging the outer ends of the piston rods —21—, (see Fig. 9), the abutment —23— being rigid or integral with the carriage, while the other abutment —24— is adjustable, it being pivoted at —25— to suitable lugs on the under side of the carriage and provided with a laterally 85 projecting shoulder —26— registering with an adjusting screw —27— in said carriage for taking up any lost motion between the abutments and piston rods.

As shown in Fig. 9, the central portion of the section —8— of the main supporting frame is provided with an upright pendent pump case —28— suitably secured to the under side thereof directly under the central portion of the cylinder —19— for receiving 95 a rotary valve —29— having an eccentric bore —30—, in which is mounted a rotary impeller —31— coaxial with the axis of the valve and, therefore, eccentric to the bore thereof, said impeller being provided with 100 one or more, in this instance four, radial blades —32— spring-pressed outwardly against the walls of the bore —30— by coil springs —33—, Fig. 11.

The valve —29— is fitted to turn freely in 105 the central bore, as —28—, of the pump case and is provided with a pair of ports —34— at diametrically opposite sides of the impeller, but mainly to one side of the center of the bore —30— for communication with 110 corresponding ports —35— in diametrically opposite side of the pump case —28—.

These ports —35— communicate with upright passages —36— in the pump case —28— which ports extend through the superposed portions of the section —8— where they communicate with radial ports —37— in the adjacent side of the cylinder —19— at opposite ends of the piston —20— so that if the valve —29— is in the position shown in 120 Fig. 11 and the impeller is rotated in the direction indicated by the arrow in the same figure, the circulating fluid, as oil, will be drawn from the right-hand end of the cylinder through the corresponding passage 125 —36— into the impeller chamber and then forced through the left-hand passage —36— into the cylinder —19— at the left-hand end

of the piston —20—, thereby forcing said piston to the right (Fig. 9) and effecting a similar movement of the carriage —16— in the same direction, while on the other hand 5 if the valve —29— is rotated a half revolution to reverse the position of its ports —34—, the movement of the piston —20— and carriage will be correspondingly reversed.

10 The pump case —28— and cylinder —19— are secured, respectively, to the lower and upper faces of the intermediate portion of the frame section —8— by bolts —38—, Figs. 10 and 11, and, therefore, become a 15 rigid part of the frame, but separable for convenience of manufacture.

The upper and lower ends of the valve —29— are closed by suitable plates or end heads —39— to prevent leakage of the pressure fluid and are preferably secured to said valve —29— to rotate therewith. The impeller —31— is preferably driven from the grindstone shaft —11— through the medium of suitable connections, and for this 25 purpose is secured to an upright shaft —40— which is journaled in the pump case —28— and is provided with a worm gear —41— keyed thereto.

30 Meshing with the worm gear —41— is a worm —42— (Fig. 3) on a horizontal shaft —43— which is journaled in suitable bearings on the pump case —28— and frame section —8—, and is provided with a grooved pulley —44— connected by a belt —45— to 35 a pulley —46— on the grindstone shaft —11— (see Fig. 4), thus rotating the impeller continuously as long as the grindstone is in operation.

Automatic reverse control.

40 A horizontal rock shaft —47— is journaled in the central portion of the frame section —8— between the pump case —28— and cylinder —19—, and preferably in the same 45 plane as and at right angles to the axis of the impeller shaft —40—, and is provided at its inner end with a double stop pawl or escapement —48— so as to rock therewith for alternately forcing the opposite ends of 50 the pawl into the path of a yielding abutment —49— which, in this instance, constitutes a part of the lever —50— eccentrically pivoted at —51— to the top face of the upper disk or plate —39— of the rotary valve 55 ring —29— so as to rotate with said ring, the lever —50— being also provided with a brake-shoe —52— for frictional engagement with the inner cylindrical walls of the pump case —28— when the abutment —49— 60 counters either end of the stop pawl —48—, as shown more clearly in Fig. 10.

The friction produced by the rotary impeller —31— and also that produced by the circulation of the oil tends to rotate the

valve ring —29— and lever —50— thereon, 65 but they are prevented from such rotation by the engagement of the abutment —49— with one end or the other of the stop pawl —48— and it, therefore, follows that if the holding end of the stop pawl is rocked 70 from its holding position, the opposite end will be forced to a similar holding position, thus permitting the rotation of the valve ring —29— and lever —50— through a substantially half revolution for reversing the 75 position of the ports —34— relatively to the ports —35— and thereby reversing the direction of flow of the fluid and effecting a corresponding reversal of movement of the piston —20— and carriage —16—. 80

The free end of the lever —50— is spring-pressed forwardly in the direction of rotation by means of a spring —53— to release the brake-shoe —52— from frictional engagement with the inner walls of the pump 85 case —28— as soon as either end of the pawl —48— is withdrawn from holding engagement with the abutment —49—.

On the other hand, when the abutment —49— encounters either end of the pawl 90 —48— at the end of each half revolution of the valve ring —29—, it will automatically force the brake-shoe into frictional engagement with the inner wall of the pump case —28—, thereby aiding in stopping the further rotation of the valve ring —29— until the pawl —48— is again shifted. 95

The rock shaft —47— extends forwardly through the front side of the frame section —8—, as shown in Figs. 3 and 12, and is 100 provided with an upwardly projecting radial arm —54— adapted to be operated by suitable devices on the front side of the carriage —16—.

As shown more clearly in Figs. 3 and 12, 105 these devices consist of a pair of spaced bell-crank levers —55— having their upper ends pivoted at —56— to a forwardly projecting portion —57— of the carriage —16— and their lower ends provided with pins or 110 lugs —58— disposed at opposite sides of the upper end of the arm —54—, said levers being adjustable about their pivots —56— by means of adjusting screws —59— for permitting the operation of the stop pawl 115 —48— and consequent reversal of the valve ring —29— earlier or later in the movement of the carriage in either direction, as may be desired.

It is now clear that the pins —58— not 120 only control the direction of flow of the fluid from the impeller to the cylinder —19— for operating the piston —20— and carriage —16— in reverse directions, but also determine the amount of movement of the carriage in either direction, such movement being preferably limited to a distance slightly less than the face width of the grindstone 125

so that the lens which is supported indirectly by the carriage will remain in contact with the grindstone in all positions of movement of the carriage.

5 *Lens-holding means and operating means therefor.*

The carriage —16— is provided at its opposite ends with upwardly and rearwardly projecting arms —60— carrying at their upper ends pivotal screws —61— engaging and supporting the opposite ends of a forwardly and rearwardly oscillating frame —62— for receiving and supporting a lens-holder —63— and operating means therefor, the frame —62— being hollow and fluid-tight to receive a quantity of oil or other lubricant for lubricating the various moving parts therein.

20 Secured to one end of the frame —62— above its axis of movement is an extension —64— in which is journaled a shaft —65— to which rotary motion is transmitted from the grinder shaft —11— through the medium of the shaft —43— and suitable connections between the shaft —43— and —65—.

As illustrated more clearly in Figs. 1, 4, 5 and 9, these connections consist of a worm —66— on the shaft —43— meshing with a worm gear —67— on the lower end of an upwardly extending flexible shaft —68—, the upper end of which is provided with a spiral gear —69— meshing with a similar spiral gear —70— on the shaft —65—.

35 The lower end of the flexible shaft —68— is journaled in a yoke —71— which is pivotally hung upon the shaft —43—, the upper end of said shaft being journaled in a yoke —72— which is journaled upon an eccentric portion of a rock shaft —73— having its ends journaled in a pair of forwardly projecting arms —74— forming a part of the extension —64— of the oscillating frame —62—, the rock shaft —73— being provided

45 with radially extending handles —75— by which it may be rocked to shift the gear —69— into and out of mesh with the gear —70— for stopping and starting the lens-holder independently of the grindstone or

50 reversing mechanism for the carriage —16—. The outer end of the shaft —65— is provided with a hand-wheel —76— by which the shaft —65— and parts operated thereby may be adjusted in the initial setting up of

55 the machine.

The lens-holder —63— comprises a pair of coaxial lens-clamping members —77— and —78— arranged end to end and having their adjacent ends provided with suitable pads 60 for receiving and retaining the lens or lenses between them, said lens-clamping members being operatively connected to separate coaxial rotary spindles —79— and —80— to rotate therewith.

5 These spindles are journaled in suitable

bearings in the lower portion of the oscillating frame —62— some distance below and parallel with the axes of the pivotal screws —61— for said frame and also parallel with the axis of the main driving shaft 70 —65—, each spindle being connected by a similar train of gears —81— to the opposite ends of a secondary driving shaft —82—, the latter being journaled in the upper portion of the frame —62— parallel with the 75 axes of the spindles —79— and —80—, but a predetermined distance to one side of the axis of the main driving shaft —65—, the gears —81— being so constructed and arranged as to drive both of the spindles 80 —79— and —80— in the same direction at one-half the speed of the secondary driving shaft —82—.

The adjacent ends of the shafts —65— and —82— are spaced apart and are provided with similar disks or crank arms —83— and —84— pivotally, but eccentrically, connected with each other by suitable means, preferably a link —85—, for transmitting rotary motion from the main driving shaft —65— to the secondary driving shaft —82— and causing the secondary shaft —82— and lens-holder driven thereby to revolve in the same direction as the driving shaft, but at different speeds during 90 each revolution.

For example, in grinding an elliptical lens if the lens-holder is driven at the same rate of speed during each revolution, the edges adjacent the ends of the shorter axis 100 will not grind down as rapidly as those adjacent the ends of the longer axis, due mainly to the difference in arc of contact with the stone and also to difference in thickness of the lenses at these points, and in 105 order to overcome this inequality in the speed of grinding and to cause all portions to be ground to the desired form at about the same time, the disks —83— and —84— and their shafts —65— and —82— are arranged and 110 connected in such offset relation as to cause the lens to rotate with slower speed when grinding across the ends of the short axis than when grinding across the ends of the long axis.

115 That is, the speed of rotation of the lens is greatest when grinding across the ends of the longer axis and is sufficiently reduced or retarded when grinding across the ends of the shorter axis to effect a uniform grinding so that all portions will be finished at about the same time.

The spindle —79— is provided with an anti-friction end-thrust bearing —86— interposed between the hub of the gear —81— 125 thereon and the adjacent outer end of the frame.

The lens-clamping member —77— is connected to its corresponding spindle —79— by means of a coupling —87— having re- 130

duced ends which enter central sockets in the adjacent ends of the clamping member —77— and shaft —79—, respectively, as shown more clearly in Fig. 6, the coupling 5 —87— being locked to the adjacent end of the shaft by means of a pin —88— to cause them to rotate together.

A lens pattern —89— is mounted upon the coupling —87— between its enlarged central 10 portion and adjacent end of the clamping member —77— and together with said coupling member may be locked to rotate therewith by any suitable locking means, not necessary to herein illustrate or describe.

15 The clamping member —78— is provided with a central opening for receiving the adjacent reduced end of the spindle —80— to which it is locked to rotate therewith by means of a pin —90—.

20 The spindle —80— and its corresponding clamping member —78— are movable axially to clamp and release the lenses, said spindle being provided with an anti-friction end-thrust bearing —86'—, similar to the 25 bearing —86—, and interposed between a sleeve —91— on the outer end of said spindle and a set of coil springs —92— in the hub of the adjacent gear —81—, the springs serving to prevent excessive pressure of the 30 lens-clamping members —77— and —78— upon the lenses to reduce the liability of breakage of said lenses.

Suitable means, operable at will, is provided for shifting the spindle —80— and its 35 clamping member —78— axially and automatically locking it in any of its adjusted positions, said means consisting, in this instance, of an upright rock arm —93— arranged within the corresponding end of the 40 frame —62— and pivotally mounted at its upper end upon a cross pin —94— and having its lower end bifurcated to extend partially around the spindle and provided with pins or lugs —95— engaging in an annular 45 groove —96— in the sleeve —91—, the sleeve being held against endwise movement relatively to the spindle —80— between the anti-friction bearing —86'— and a cap screw —97— on the outer end of said spindle, as 50 shown in Fig. 6.

A rock shaft —97— is journaled at its opposite ends in the front and rear sides of the frame —62— some distance below and parallel with the pivotal pin —94— and extends through relatively larger openings —98— in corresponding sides of the rock arm —93—, the central portion of the rock shaft being enlarged radially and provided with opposite upwardly and inwardly projecting cams or eccentric bearings —99— which engage contacts or pins —100— on superposed portions of the rock arm —93—, the cams —99— and pins —100— being so arranged as to cause the pressure of the pins 60 —100— to act radially of the rock shaft

—97— so as to automatically lock the rock arm in any position of adjustment.

One end of the rock shaft —97— is secured in a bushing —101—, Fig. 8, which is journaled in the adjacent side of the frame 70 —62— and extends to the outside thereof where it is provided with an operating handle —102— for turning the rock shaft in one direction or the other and thereby transmitting rocking motion to the lever —93— 75 to effect a corresponding axial adjustment of the spindle —80— and the lens-clamping member —78—.

Suitable means is also provided for automatically rocking the lower end of the frame 80 —62— toward the grindstone to cause the lens to contact therewith, and for this purpose a lever —103— is pivoted at —104— to the outside of the upper portion of the shield —4— and is provided with a downwardly projecting arm —105— connected by a link —106— to an arm —107— on the frame —62—, as shown more clearly in Figs. 1 and 2, said lever —103— being provided with a forwardly and rearwardly extending 90 guide —108— upon which is adjustably mounted a weight —109—, the latter being held in its adjusted position by a set screw —110—.

The periphery of the pattern —89— is 95 adapted to ride against a suitable back-rest —111— which is mounted in a suitable guide —112— on the carriage —16— and may be adjusted by means of a hand-piece —113—, said carriage being also provided with a 100 suitable truing device —114— capable of being adjusted at will to keep the face of the grindstone smooth and true.

Operation.

105

Figs. 13 to 20, inclusive, show, respectively, the relative positions of the disks at starting and at the end of each eighth turn during one complete revolution, the relative arcs of movement at the end of each successive eighth turn being indicated by degrees, while each half of the lens which is driven at one-half the speed of the disk —84— is correspondingly divided into eight (8) equal angles, each representing an eighth 115 turn of the disk —84—.

As previously explained, the lens rotates one-half revolution during each complete revolution of the disks, which, when connected in the manner shown and adjusted in 120 certain relation to the lens-holder, causes the lens to rotate at a maximum slower speed than its driving disk —84— when grinding across the ends of the short axis and at a maximum higher speed corresponding to that of the driving disk when traveling across the ends of the long axis, and it, therefore, follows that the two disks will be rotating at approximately the same speed and the lens at half that speed when grinding 125 130

across the ends of an axis substantially midway between the ends of the short and long axis, or at an angle of about forty-five (45°) degrees, relatively to said short and long axis.

This intermediate axis may be termed the "neutral" axis and is indicated by 0. When one end of the neutral axis is at the grinding point, the disks will be approximately in the position shown in Fig. 13, and which may be termed the starting position in which a direct line between the pivotal points of the links —85— and their respective disks is approximately parallel with a direct line drawn between the axes of the shafts —65— and —82—.

It will be remembered that although the driving disk —83— may be rotated at constant speed, the speed of the driven disk —84— will be variable, while the speed of rotation of the lens-holder and lens will be in constant ratio of one-half to one of the driven disk, and for convenience of description, the driven disk is indicated in full lines and the driving disk in dotted lines, the radial lines indicating the relative arc of movement of the driving disk at the end of each successive eighth turn of the driven disk from its starting position.

For example, if the driven disk —84— is moved through the first eighth turn or through an arc of forty-five (45°) degrees, as shown in Fig. 14, the driving disk —83— will have been moved through an arc of approximately fifty-one (51°) degrees, during which the grinding point of the lens will have been moved from one end of the neutral axis, or zero, one-sixteenth ($\frac{1}{16}$) of a turn or one-eighth of a semi-ellipse toward the corresponding end of the short axis, showing that the driven disk —84— has been retarded six (6°) degrees behind that of the driving disk with a result that the speed of movement of the lens has been correspondingly retarded.

In like manner as the driven disk is moved through the next succeeding eighth turn or arc of ninety (90°) degrees, the driving disk —83— will have moved through an arc of one hundred and seventeen (117°) degrees, during which the lens will have moved another sixteenth turn, bringing the end of the short axis at the grinding point and showing that the driven disk has been retarded twenty-seven (27°) degrees behind that of the driving disk during the second eighth turn, as shown in Fig. 15, with a corresponding retardation of the lens —a—.

During the third eighth turn of the driven disk —84—, as indicated in Fig. 16, the driving disk will have been moved through an arc of one hundred and ninety-three (193°) degrees, showing that the driven disk has been retarded behind the driving disk fifty-eight (58°) degrees with a corre-

sponding retardation of the lens during the third sixteenth turn.

As the driven disk —84— moves through the next eighth turn, completing the first half revolution or one hundred and eighty (180°) degrees, the driving disk —83— will have moved through an arc of two hundred and eighty-two (282°) degrees, showing that the driven disk has been retarded the difference of fifty-two degrees (52°), or nearly the same amount of retardation as in the travel from the second eighth to the third eighth turn, thus causing the maximum retardation across the end of the short axis of the lens where it is most desired.

It will be noted that the speed of movement of the driven disk progressively reduces through the first, second and third eighth turns, and that it begins to increase during the fourth eighth turn, or from the position shown in Fig. 16 to that shown in Fig. 17.

In Fig. 18, it will be seen that this increased speed of the disk —84— continues during the next eighth turn in which the driving disk —83— will have been moved through an arc of approximately two hundred and sixty-one (261°) degrees, showing that the retardation of the driven disk —84— is approximately thirty-six (36°) degrees.

In the next eighth turn shown in Fig. 19, the difference will be twenty-eight (28°) degrees; Fig. 20 four (4°) degrees, showing that the speed of the driven disk is gradually building up to that of the driving disk which it equals on the last eighth turn, or in passing from the position shown in Fig. 20 to that shown in Fig. 13.

During this complete revolution of the disks —83— and —84—, the lens will have been moved from the zero position at one end of the neutral axis to the zero position at the opposite end of such axis, the operation being repeated during the next revolution of the disks, said operations recurring until the lens is ground to the desired form and size.

This differential speed motion is particularly efficient in finishing the grinding operation of all portions of the lens at practically the same time, but it is evident that other means for producing this differential motion may be devised without departing from the spirit of this part of my invention, and, therefore, I do not wish to limit myself to the construction shown.

As the lens is rotated against the grindstone, it produces a recurrent oscillation of the frame —62— about the axis of its pivotal pins —61— which are alined with the meeting faces of the gears —69— and —70—, as shown more clearly in Fig. 6, the object of which is to maintain a uniform rotation of the driving shaft —65— and its

disk —83—, as otherwise the oscillation of the frame would cause more or less interruption or unsteadiness in the rotation of said shaft and disk and parts driven thereby.

5 Another important feature of the invention consists in the means, as the screws —59—, for adjusting the arms —55— to vary the length of travel of the carriage —16— at will.

10 It is also evident that when it is desired to open and close the lens-clamping jaws, it is simply necessary to shift the lever —102— by hand in one direction or the other, it being automatically locked in any position of 15 adjustment by the engagement of the pins —100— with the bearing members —99—.

In machines of this character, the pattern and its support are usually provided with means for placing them in but one fixed relation which, as previously explained, conforms to a certain position of the disks —83— and —84— so that in placing the lenses in the machine for grinding, it is only necessary to properly register them with 25 the pattern.

The grinding operation may then proceed in the manner described without further attention from the attendant until the lens is ground to the desired size and form as determined by the pattern and the position of 30 its back-rest relatively to the plane of grinding which may be regulated by any well-known form of adjusting device, as —113—.

What I claim is:

35 1. In an edge-grinding machine for elliptical lenses, the combination with a grinder, of a rotary lens-holder, and means for rotating said holder at such different speeds during different parts of each revolution as 40 to cause all portions in the periphery of the lens to travel against the grinder at such a rate of speed that all portions of said periphery shall be completed at practically the same time and means for maintaining 45 the periphery of the lens against the grinder.

2. In a machine for grinding the edges of lenses having axes of different lengths, the combination with a grinder, of a rotary lens-holder, and means for rotating said lens-holder under gradually diminishing speed as 50 the point of contact of the lens with the grinder passes from the end of the longer axis toward the end of the shorter axis.

3. In a machine for grinding the edges of lenses having axes of different lengths, the combination with a grinder, of a rotary lens-holder, and means for rotating said lens-holder under gradually decreasing speed as 55 the point of contact of the lens with the grinder passes from the end of the longer axis toward the end of the shorter axis.

4. In a machine for grinding the edges of lenses having axes of different lengths, the combination with a grinder, of a rotary lens-holder, and means for rotating said lens- 60

holder under gradually increasing speed as the point of contact of the lens with the grinder passes from the end of the shorter axis toward the end of the longer axis and with gradually decreasing speed as said point of contact passes from the end of the longer axis toward the end of the shorter axis. 70

5. In an edge grinding machine for lenses, the combination with a grinder, of a rotary lens-holder, and means for rotating said holder including eccentrically connected driving and driven members rotating in the same direction about parallel axes offset one from the other. 75

6. In an edge grinding machine for lenses, the combination with a grinder, of coaxial rotary lens-clamping members and means for forcing one of said members endwise toward the other member including co-operative rockers movable about parallel offset axes, and bearing one against the other at 80 opposite sides of a direct line between said axes. 85

7. In an edge grinding machine for lenses, the combination with a grinder, of coaxial rotary lens-clamping members, separate driving shafts therefor, a rocker arm pivoted to swing in a plane parallel with one of said shafts, connections between said rocker arm and shaft to move the latter axially, and a manually-operated rocker in operative engagement with the rocker arm for rocking the same in opposite directions. 90

8. In an edge grinding machine for lenses, the combination with a grinder, of coaxial rotary lens-clamping members, separate driving shafts therefor, a rocker arm pivoted to swing in a plane parallel with one of said shafts and provided with bearings at opposite sides of its pivot, and a manually-operated rocker having cam faces at opposite sides of its axis engaging said bearings. 100

9. In an edge grinding machine for lenses, the combination with a grinder, of coaxial rotary lens-clamping members, separate driving shafts therefor, one of the shafts being movable axially, means including gears on the shafts for driving the same, one of the gears being movable axially with its shaft, an end-thrust bearing for the axially movable shaft, and yielding connections between the end-thrust bearing and adjacent gear. 110

10. In a machine for grinding the edges of lenses, the combination with a rotary grinder, a carriage movable parallel with the axis of the grinder, a frame pivotally mounted on the carriage to swing toward and from the grinder, separate coaxial shafts journaled on the frame, lens-clamping members on said shafts, power-driven means for reciprocating the carriage, and means for transmitting motion from the grinder shaft to the first-named shafts, said means includ- 115

120
125
130

- ing coöperative rotary members revolving in the same direction about parallel axes offset one from the other, and means for connecting the last-named members to each other.
- 5 11. In a machine for grinding the edges of lenses, the combination with a rotary grinder, a frame pivoted to swing about an axis parallel with that of the grinder, a rotary lens-holder mounted on the frame parallel with and some distance to one side of said axis, and driving means for said lens-holder including a pair of gears meshing at a point in approximate alinement with said axis.
- 10 12. In an edge-grinding machine of the character described, the combination with a grinding element, a work-holder, and a swinging support therefor, of means for rotating the workholder including a pair of rotary driving members contacting at a point in approximate alinement with the axis of movement of said support.
- 15 13. In an edge-grinding machine for elliptical lenses, the combination with a grinding element and a rotary lens-holder, of means for rotating said holder so as to cause the portion of the lens adjacent the ends of the short axis to travel against the grinding
- 20 element at a slower rate of speed than that with which the portions adjacent the ends of the long axis travel against the same element.
- 25 14. In an edge-grinding machine for elliptical lenses, the combination with a grinding element and a rotary lens-holder, of means for rotating said holder so as to cause the edges of the lens at the ends of the shorter axis to travel past the grinding point at a slower rate of speed than that of the edges at the ends of the longer axis past the same point.
- 15 15. In an edge-grinding machine for elliptical lenses, the combination with a grinding element and a rotary lens-holder, of means for rotating said holder at such variable speed as will maintain an approximately constant speed of all portions of the periphery of the lens past the grinding point.

In witness whereof I have hereunto set my hand this 15th day of May, 1916. 50

ELI MAYNARD LONG.

Witnesses:

ALBION W. NEWELL,
H. E. CHASE.
